MILEAGE RECORD HOLDER FOR AUTOMOBILES

Original Filed July 8, 1929

Inventor:
Nathan M. Stone,

Charles J. Hervey,

115 Attn.

UNITED STATES PATENT OFFICE

NATHAN M. STONE, OF CHICAGO, ILLINOIS

MILEAGE RECORD HOLDER FOR AUTOMOBILES

Application filed July 8, 1929, Serial No. 376,791. Renewed October 24, 1931.

The invention relates to mileage record holders for automobiles, and its principal object is to provide improved means for holding a pad of paper in convenient position in an automobile for ready access thereto, whereby notations may be made thereon regarding the mileage of the automobile as shown by the speedometer. It is well known that it is important to completely change the oil in the crank case of an automobile after it has been driven a predetermined number of miles, to grease the car, and to water the battery, and various attempts have been made to keep a record of the mileage, so that proper attention may be given the automobile at the proper time.

In accordance with the present invention, a receptacle is provided for holding a pad of paper which has clamping means, whereby it may be secured to the steering post of the car in convenient position for access whenever it is required to make notations on the pad. The receptacle is provided with a cover having sight openings therein, through one of which is permanently displayed advertising matter, and through the other of which is displayed a portion of the pad containing the notations.

The invention consists in the several novel features hereinafter fully set forth and claimed.

The invention is clearly illustrated in the drawings accompanying this specification in which—

Figure 1 is a plan of a mileage recorder embodying a simple form of the present invention;

Fig. 2 is an under plan of the device; Fig. 3 is a plan of the device opened out to expose the interior thereof, a certain advertising card and backing piece being partially broken away to illustrate parts which would be otherwise hidden from view;

Fig. 4 is a vertical cross section taken on the line 4—4 of Fig. 1, and showing the device clamped to a fragment of the steering post of an automobile; and

Fig. 5 is an end view looking in the direction of the arrow 5 in Fig. 1 with a certain clamping loop omitted.

Referring to said drawings, the reference character 6 designates a receptacle composed of bottom and top members 7 and 8 hinged together at 9. The two members 7 and 8 are formed of light gauge sheet metal struck up with suitable dies, and the member 7 is formed with marginal flanges 10, 11 and 12 which extend at right angles to a bottom wall 13 and form a rectangular or square box-like structure. As a preference, the bottom wall 13 may be formed with a notch 14 adjacent one edge of which furnishes means whereby the top member of the receptacle may be readily pushed open to obtain access to the interior of the receptacle.

The top or cover member 8 is formed with side flanges 15 which are struck up from its top wall 16, which flanges, when the receptacle is closed, overlap the side flanges 11 of the box-like portion 7 of the receptacle. The top wall 16 of the cover portion 8 is formed with two sight openings 17 and 18 through which the advertising material and the pad containing the mileage data are visible. The ends of the top wall 16 are bent back upon themselves to form lips 19 that extend parallel with the top wall and provide grooves for receiving the ends of a transparent sheet of material 20, such as celluloid, a business card 21 and a piece of backing material 22, such as metal placed under the top wall 16 and held thereon by the lips 19. The business card 21 may contain suitable printed matter which is displayed through the sight opening 17, and both said business card 21 and the metal backing piece 22 are formed with sight openings 23 and 24 co-incident with the sight opening 18 in the cover member 8, whereby a portion of the memorandum pad 25 is visible at all times through the sight opening 18. The side flanges 11 and 15 extend slightly beyond one end of the box and cover portions in the form of ears 26 through which are inserted rivets 27 that hingedly connect the two members of the receptacle together.

The memorandum pad 25 may comprise a number of cards or sheets of paper 28, one corner of the uppermost one of which is shown as bent upward in Fig. 3 to show the corner of the one below, and said sheets are fastened

together by staples or the like 29. The pad 25 is of a size to fit conveniently in the box or lower member 7 of the receptacle. On each side of the median line of the sheets 28 (defined by the staples 29) are printed appropriate words having reference to the changing of oil, the greasing of the car, and the watering of the battery, as, for instance, the words, "Oil Changed", "Greased", "Bat. Watered", adjacent which words are blank spaces which may be written upon by the user to indicate the mileage shown by the speedometer at the time oil is changed, the car is greased, or the battery is watered. The notations at one side of the median line of the pad are always visible through the sight opening 18, and whenever it is necessary to make a new notation, this may be done upon the opposite end of the same sheet containing present notations and the pad turned around to expose the new notations through the sight opening 18, and when both ends of a sheet have been filled in, the half of the sheet upon which the first notion was made may be torn off and new notations may be made on the exposed portion of the sheet therebelow.

In using the device, the person makes notations on the exposed portion of the pad indicating the mileage shown by the speedometer at the time of changing oil, greasing the car, or watering the battery. This information is always before him and he can readily determine when the automobile has been driven through the predetermined number of miles allowed before attention must be given to the changing of oil, greasing the car, or watering the battery.

For securing the device upon the steering post of an automobile, a clamp 30 is provided which, as shown, comprises a bracket member 31 spot welded, as at 32, or otherwise secured to the bottom portion 13 of the box-like member 7 of the receptacle, and a flexible metal strip 33 bent in the form of a loop 34 which surrounds the steering post 35 of the automobile. The bracket member 31 is formed with a yoke-like portion 36 through which the ends of the flexible strip 33 pass, and a bolt 37 extends through apertures in said yoke-like portion 36 and enters apertures 38 formed in the strip 33. One end of the strip may contain a number of apertures in order to make the loop adjustable for steering posts of different diameters. The loop 34 being placed around the steering post and the ends of the strip passed through the yoke-like part 36, the bolt 37 may be passed through said yoke-like portion and through two opposite perforations in the end portions of the strip, a nut 39 placed upon the bolt, and the latter tightened up to securely clamp the device upon the steering post.

I claim as new, and desire to secure by Letters Patent:

1. In a mileage record holder for auto-

mobiles, a pad holding receptacle adapted to contain a memo pad, and having a cover formed with cardholding means and having two sight openings therein through one of which the pad is visible and through the other of which the card is visible, said receptacle having clamping means adapted to secure the receptacle to the steering post of an automobile.

2. A mileage record holder for automobiles comprising a pad holding receptacle, a yoke-like bracket member secured to the underside of the receptacle, a strip of flexible metal extending through the yoke part of said bracket member and formed with perforations adjacent its ends, and a bolt extending through said yoke part of the bracket member and through opposite perforations in the flexible strip and adapted to clamp said flexible strip upon the steering post of an automobile.

3. A mileage record holder for automobiles comprising a pad holding receptacle composed of two hinged together members having overlapping side flanges, one of said members being formed with two sight openings and card retaining lips, and a card secured behind said sight openings by said card retaining lips and having a sight opening registering with one of the sight openings in said member of the receptacle, and said card bearing advertising matter visible through the other sight opening of said member of the receptacle.

4. A mileage record holder for automobiles comprising a pad holding receptacle composed of two members hinged together and both provided with overlapping side flanges, one of said members being provided with two sight openings and formed with card holding lips, a transparent sheet, a business card and a metal backing plate secured behind the member having the sight openings by said card retaining lips, said card and backing plate having sight openings registering with one of the sight openings in said member of the receptacle and said card having advertising material visible through the other sight opening of said member.

5. A mileage record holder for automobiles comprising a pad holding receptacle having top and bottom members, the top member being provided with two sight openings, and a business card secured to said top member and having an opening registering with one of the sight openings in the top member and bearing advertising matter visible through the other sight opening of the top member, said bottom member being adapted to contain a memo pad visible through the registering openings in the top member and business card.

6. A mileage record holder for automobiles comprising a pad holding receptacle formed to two hinged together members provided

with overlapping side flanges, one of which is formed with two sight openings, a card secured on the member having the sight openings and provided with a sight opening registering with one of the sight openings in said member of the receptacle, said card bearing advertising matter visible through the other sight opening of said member of the receptacle.
